UNITED STATES PATENT OFFICE.

DANIEL J. MURNANE, OF CHICAGO HEIGHTS, ILLINOIS.

COMPUTING-CHART FOR STORE-FRONT CONSTRUCTIONS.

1,277,634.

Specification of Letters Patent. Patented Sept. 3, 1918.

Application filed May 11, 1916. Serial No. 96,866.

To all whom it may concern:

Be it known that I, DANIEL J. MURNANE, a citizen of the United States, residing at Chicago Heights, in the county of Cook and State of Illinois, have invented a new and useful Improvement in Computing-Charts for Store-Front Constructions, of which the following is a specification.

My invention relates, more particularly, 10 to a computing chart for determining quickly and accurately the cost of the various framing-members of store-front constructions, for any given design and size of structure.

15 Store-front constructions, as commonly provided, are formed of a number of different varieties of framing-members, the figuring of the cost of which for the various designs of store-front constructions and the 20 various sizes of such constructions, is a difficult and painstaking operation requiring relatively great skill and considerable time, these conditions being augmented to a material degree by the fact that for each design 25 of structure and for each size of structure, different kinds or shapes of framing-elements involving different cost calculations, 30 may be used.

My object, generally stated, is to provide a 35 system of cost calculation whereby, having determined the design of the store-front construction and its dimensions and the kinds of framing-members desired to be used, the cost of such members for the particular design and of the particular dimensions, may be accurately and quickly determined by a 40 relatively unskilled person.

As a preface to further explanation of the invention it may be stated that in use 45 my improved system would be employed by a manufacturer, dealer or constructor to furnish the facilities for determining costs as hereinbefore explained, in connection with the particular types or style of framing-members which he manufactures, deals in or uses, and to this end the data forming the basis of the system for the particular conditions presented would be based on these 50 particular forms of framing-elements and the various combinations in which it might be desired to use them.

Referring to the accompanying drawings, 55 Figures 1, 2 and 3 constitute plans of one of a number of different designs of store-front constructions, Fig. 1 showing the construc-

tion by a front perspective view, Fig. 2 showing it in edge elevation, and Fig. 3 showing it in plan section; and Fig. 4 showing the chart for coöperation with the plans of Figs. 1, 2 and 3 to determine the cost of 60 the various framing-members required to be used in various constructions to produce the framing of this particular design of store front constructions of given dimensions.

In practice, by preference, there would 65 be provided for each different design of store-front construction, plans showing the general arrangement of the framing-members for this particular design of construction, as for example, those shown in Figs. 1, 70 2 and 3, and preferably other data as hereinafter explained, and for use in connection with each set of such plans, a chart would be provided for coöperation therewith, with tables presenting figures for the various 75 forms of framing-members for the construction of this particular design, by which the cost of such members in different combinations may be readily determined for any given size of store-front construction of 80 such design.

In illustrating my invention I have chosen to show it as applied to only one design of store-front construction and that one comparatively simple, so as to render a description of the invention clearly understandable, though, as above stated, a set of plans for each design of store-front construction would be provided and for coöperation therewith, cost charts with data applicable to the particular design of store-front construction in connection with which 85 it is to be used.

The chart of Fig. 4 is, by preference, provided in three divisions, division 5 relating 90 to the transom materials, or, in other words, the upper portion of the store-front construction and which is generally comprised within the lines 6 and 7 of Fig. 1; division 8 relating to the show-window section of the 95 construction, or, in other words, that part contained generally within the lines 7 and 9 of Fig. 1; and division 10 relating to the bulkhead, or, in other words, that portion 100 of the store-front construction included generally within the lines 9 and 11 of Fig. 1.

Considering first the division 5 of the chart, a horizontal row 12 of figures spaced apart and indicating the width (preferably 105 in feet) of the transom-section of the con- 110

struction of Fig. 1, is presented, and at right angles thereto and arranged in a vertical row or column 13 are figures spaced apart and representing preferably in inches different heights of transom sections. Arranged in vertical rows 14 in line with the various numerals in row 12, are series of numerals representing price denominations, as for example dollars, the various figures in the rows 14 being spaced apart vertically the same distance as in the case of the row 13 of figures. The rows 14 of figures are those which upon previous calculation have been determined to be the cost prices of the various frame-members of particular constructions and provided in particular combinations, for the transom-section of the store-front construction provided of a width within the limits specified in row 12, for transom-sections of varying heights within the limits set forth in row 13. For example, and referring particularly to the chart shown at 5 in Fig. 4, the chart figures are based upon certain constructions of transom-bar covering, division-bars, sash and head and side-jamb coverings, as stated in the upper part of the chart-section 5, and, by way of example, it may be stated that the user of the chart upon determining the width and height of the transom-section, which would correspond to the arrangement shown in Fig. 1, and desiring to base the construction of this transom-section upon the specification of parts as above stated, and assuming the transom to be 22' long and 44" high, may readily determine the cost of the framing materials for this size and design of transom by reference to the chart just explained which shows in the column 14 in vertical alinement with 22' (representing width in feet) and in horizontal alinement with 44" in column 13, the number 55 which represents the cost thereof figured out from previous calculations.

45 Provision is made in division 5 of the chart for indicating the deductions to be made from the figures contained in the section just explained, where, for example, one of the elements (in the particular example illustrated transom-bar covering No. 415) is omitted. These deductions, represented by the line 15 of figures, are for the different widths of transoms, and as will be clear from Fig. 4 are arranged in vertical alinement with the several columns 14, whereby if the particular element to which these deductions relate, is omitted, the one using the table can by merely running down the vertical column headed by the numeral which represents the width in feet of the particular transom on which he is figuring, quickly determine the deduction to be made for such omission in the particular construction being figured on. Thus, if the covering No. 415 is to be omitted in the example of transom

som above related for illustrating the manner of using the chart, the deduction would be \$10.01.

Provision is also made in division 5 of the chart for indicating the additions to be made to the amounts contained in the columns 14 where any one of a number of different substitutions for certain of the elements upon which the amounts in columns 14 are based, are made, in order that the cost of the framing-members with such substitutions of certain elements thereof, may be quickly determined. In the particular example shown, the substitutions indicated are for the transom bar covering No. 415. This table is formed of columns 16 arranged in line with the columns 14 as noted and provided for indicating the additions to be made to the amounts shown in columns 14, for the different widths of transom-sections, columns 17 at opposite ends of the columns 16 and in line with the several lines of figures in the columns 16, denoting different forms of transom-bar coverings, indicated by the numbers 420, 421, 422 and 930. The figures in the horizontal rows formed by the column 16, opposite the various numerals in the columns 17, are determined from calculations previously made, based on the use of these respective transom-bar coverings for the various widths of transom-sections indicated at the top of the columns 14. Thus, assuming that the transom is 22' wide and transom-bar covering No. 422 is to be substituted for No. 415, the user by running down the one of the columns 16 in line with the designation 22' in the line 12 of figures, and tracing across the chart from the numeral 422 in column 17 to the last-referred-to column 16 finds that the amount required to be added to the figure determined from columns 14, is \$27.81. The other additions and deductions referred to in division 5 of this chart, are self-explanatory.

110 The table 18 of division 8 of the chart and comprising the columns 19 of cost figures headed by a line of numerals 20 representing the lineal measurement, in feet, of the show-window, measured along A, B and C and D; E and F and the similar columns 21 representing the height of this portion of the store-front construction, in inches, and located at opposite ends of the group of columns 19, is of the same general character as the table including the columns 14 and is used in the same manner as explained of the latter, all of the figures in the columns 19 being calculated for the various widths and heights of show-window sections and a particular combination of framing-sections, the specifications of which, in the particular example shown, are indicated above the table 18. Thus, if the show-window section measures 27' lineally, as in the

plan shown where the transom section is 22' wide, and its height is 88", the cost of the framing-members of the specification associated therewith would be \$83.00.

- 5 Located below the table 18 is a row 22 of figures which are arranged in line respectively with the rows 19. These figures represent the deductions to be made from the figures of chart 18 in the case of the different widths of show-window sections where a certain part stated in the specification for the table 18, is omitted. Thus, referring to the particular example shown in the chart, if sill-covering No. 705 of the above specification is omitted in the case of a construction which measures 27' in width, measured as above, the deduction would be \$11.33, regardless of the height of the show-window section.
- 10 Below the line of figures 22, instructions are given to determine deductions for different heights of show-window sections where the side-jamb covering is omitted and the additions to be made where either
- 15 one of two other kinds of corner bars are employed for different heights of show-window sections, as the case may be.

In division 10 of the chart a table, represented at 23, for determining the cost of the framing-members for the bulkhead of the store-front construction is provided. This table, which is made up of the columns 24, of figures representing costs, a line 25 of figures heading columns 24 and representing in feet the width of bulkheads within certain limits measured along the lines A, B and C and D, E and F, and columns 26 arranged at opposite ends of the column 24 and indicating in inches the heights of different bulkheads, follows substantially the same plan as the tables relative to the show-window sections, and are based upon calculations as to the cost of forming the bulkheads of different heights and widths based on the specification set forth immediately above the table 23. Thus, if the bulkhead is 27' wide measured lineally as indicated of the show-window, and 18" high, the cost of the bulkhead materials on the above specification will be \$62.00.

In the plans shown in Figs. 1, 2 and 3, the various members forming the transom, show-window and bulkhead sections, in accordance with the specifications set forth at the head of each table in the chart of Fig. 4, are indicated by the numerals by which they are referred to in said specifications, and the general dimensions of the structure are given. Thus, one desiring to determine the cost of a store-front construction, after once determining the character of the store-front to be figured on and its dimensions, refers to the one of the plans which corresponds with such design and which indicates to him where the various members

referred to in the specifications presented in connection with the charts, would be located, and by referring to the chart provided for coöperation with such plans may readily figure out from such chart the cost 70 of all of the framing-members required for any size of structure within the limits of the chart and for different combinations of framing-elements as provided therein.

What I claim as new and desire to secure 75 by Letters Patent is:

1. The combination with a plan of a store-front showing a construction involving framing-members, of a table of figures for co-operation with said plan to indicate the cost 80 of the framing-members, arranged in a particular combination required for forming different sizes of store-fronts of the design shown in said plan with the framing-members arranged as represented therein, the figures 85 in said table being arranged in columns with dimension-indicating means associated with said columns and figures arranged in line with said columns for indicating the variations to be made in the figures of said 90 table where a variance from the framing-members on which the calculations in said table are based, occurs.

2. The combination with a plan of a store-front involving framing-members, of a table 95 of figures for co-operation with said plan to indicate the cost of the framing-members arranged in a particular combination required for forming different sizes of constructions of store-fronts of the design 100 shown in said plan, with the framing-members arranged as represented therein, the figures in said table being arranged in columns with dimension-indicating means associated with said columns at the heads thereof and 105 dimension-indicating means arranged in a column parallel with said first-referred-to columns and a series of columns of figures in alinement with said first-referred-to columns, a row of designating characters arranged in a column alongside of the last-referred-to columns and representing constructions of framing-members different 110 from those on which the figures in said first-referred-to table are based, the figures in 115 said last-named set of columns representing the changes in the figures of the first-referred-to table, to be made where the substitute framing-members are employed.

3. A cost-chart for indicating the cost of 120 the framing-members required for forming different sizes of store-fronts employing framing-members and of a particular design, presenting a table of figures indicating the cost of the framing-members required for forming a store-front of a particular design and size where the framing-members are employed according to a predetermined combination of varieties thereof.

4. A cost-chart for indicating the cost of 130

the framing-members required for forming different sizes of store-fronts employing framing-members and of a particular design, presenting a table of figures indicating the cost of the framing-members required for forming a store-front of a particular design and size where the framing-members are employed according to a predetermined combination of varieties thereof, and tabulated figures for coöperation with said table for indicating the variations to be made in the figures of the latter where a variance in the particular framing-members on which the calculations in said table are based, occurs.

5. A cost-chart indicating the cost of the framing-members required for forming dif-

ferent sizes of store-fronts involving framing-members and of a particular design, said chart presenting columns of figures with dimension-indicating means associated with said columns, the figures in each column indicating the cost of the framing-members where a certain combination thereof is employed, for store-fronts having different dimensions in one direction and the same dimension in another direction, and tabulated figures arranged in line with said first-referred-to columns for indicating the variations to be made in the figures of the latter where a variance in the particular framing-members on which the calculations in said first-named columns are based, occurs.

DANIEL J. MURNANE.
